UNITED STATES PATENT OFFICE.

PEABODY A. BROWN, OF DENVER, COLORADO.

ELECTRIC ALARM.

1,002,820.

Specification of Letters Patent. Patented Sept. 12, 1911.

Application filed February 5, 1909. Serial No. 476,272.

To all whom it may concern:

Be it known that I, PEABODY A. BROWN, a citizen of the United States, residing in the city and county of Denver and State of Colorado, have invented certain new and useful Improvements in Electric Alarms; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to improvements in electric alarms, my object being to provide apparatus adapted for use in cities, towns and other localities where it is desirable to alarm or notify a considerable number of 20 people, of the existence of a fire in a certain locality.

My improved system involves a series of 25 alarm boxes located in a circuit, that also contains an electromagnet, which during the giving of an alarm is intermittently energized, its circuit being made and broken one or more times, depending upon the construction of the alarm box mechanism, which contains a disk, whose periphery 30 contains a series of notches. As the disk is actuated during the giving of an alarm, a metal brush, or contact, which engages the same, is disconnected therefrom during the passage of the portion of the disk containing the space or notch between two projections or segments, thus breaking the call-box circuit every time one of the spaces registers with the position of the contact portion of said brush. Whenever the circuit is 35 broken a lever or pivoted arm, mounted adjacent to the magnet, drops and closes the circuit through one solenoid, the circuit through a companion solenoid being broken, while, when the call-box circuit is closed, 40 the armature lever is actuated to close the circuit through the second solenoid, the circuit of the first solenoid being broken. The action of the solenoid core, as the circuit is 45 closed through the solenoids, is such as to operate mechanism for opening and closing a pipe connected with a source of fluid, as steam or air, whereby the said fluid is placed in and cut off from communication with 50 whistles, which are operated to give the necessary alarm. The number of times that

the cut-off valve is opened and closed for the operation of any particular call-box, indicates the location of the said box, and also the location of the fire, since the opening and closing of the valve a given number 60 of times, results in the blowing of the whistle a corresponding number of times, each time indicating a figure or character, which to those, who understand the system, indicates the number of the call-box. 65

Having briefly outlined my improved construction, I will proceed to describe the same in detail, reference being made to the accompanying drawing, in which is illustrated an embodiment thereof.

In this drawing, Figure 1 is a view, largely diagrammatic, illustrating my improved system, and showing a series of call-boxes located in a battery circuit. Fig. 2 is a detail view, illustrating the solenoids and 70 the mechanism connected therewith for operating the valve for controlling the fluid, which blows the whistles. This view is on a larger scale than Fig. 1. Fig. 3 is a detail view, illustrating the electromagnet of 75 the call-box circuit, the parts being shown on a larger scale. Fig. 4 is a detail view, illustrating the contacts employed in making and breaking the two circuits, which may be termed the magnet and solenoid circuits. Fig. 5 is a sectional detail view, illustrating one of the trunnioned solenoids employed in operating the cut-off valve. Fig. 6 is a detail view of a disk of the character 80 employed in connection with the call-boxes. 90

The same reference characters indicate the same parts in all the views.

Referring first to Figs. 1 to 6, inclusive, let the numeral 5 designate an electromagnet, whose coils are located in a circuit containing a series of call-boxes 6. This circuit includes a source of electricity 7, from one pole of which a conductor 8 leads to the magnet 5, while from the other pole a conductor 9 leads to an adjacent call-box. 95 From the opposite terminal of the magnet 5 a conductor 10 leads to a call-box oppositely located from that connected with the conductor 9. Each of these call-boxes is supposed to contain a disk 12 (see Fig. 6), 105 having a series of recesses 13 of different lengths, the periphery of the disk being engaged by contact 14. It may be assumed that when the call box is operated this disk rotates around a spindle 15, which is con- 110

nected with one circuit wire, the metal brush or contact 14 being connected with the opposite pole of the circuit. Located adjacent to the electromagnet 5 is a metal bar 16, pivoted at 17, and carrying a carbon electrode at 18, which is located between two similar electrodes, respectively designated 19 and 20. It may be assumed that these electrodes are composed of carbon, and that they are detachably connected with suitable holders 21, 22 and 23. The lever 16 is equipped with a plate 24 of soft iron, whereby the lever readily responds to the magnetic influence. This lever 16 is pivotally connected with a stationary part 25, from which leads a conductor 26 to a brush 27 of an electric generator 28, from whose opposite brush or pole 29 leads a conductor 30 to a binding post 31, mounted upon a box 32, inclosing two solenoids 33 and 34. From the binding post 31, inside the box, leads a conductor 33 to a pin 35, upon which a bar 36, located adjacent to the two solenoids, is pivoted. These solenoids are trunnioned on a suitable support, their casings 37 having laterally projecting journals 38, which engage parts 39 and 40 respectively (see Fig. 5). Located adjacent to the solenoid 33 is a contact 41, from which leads a conductor 42 to a terminal 43 of the solenoid 34, while from the other terminal 44 of the solenoid 34 leads a conductor 45 to a binding post 46 mounted upon the box 32. From this same binding post, and located outside of the box, leads a conductor 47 to the electrode 19. Located adjacent to the solenoid 34 is a contact 48 similar to the contact 41, from which a conductor 49 leads to a terminal 50 of the solenoid 33. From the opposite terminal 51, of the last named solenoid leads a conductor 52 to a binding post 53 mounted upon the box 32. From this binding post outside of the box leads a conductor 54 to the electrode 20. The cores or rods 55 and 56 of the solenoids 33 and 34 are pivotally connected, as shown at 57 and 58 with the opposite extremities of the lever 59, fulcrumed at 60, and having an arm 61 pivotally connected, as shown at 62, to the rod 63, whose opposite extremity is pivoted, as shown at 64, to one end of an arm 65, whose opposite extremity is connected, as shown at 66, with a cut-off valve 67, for controlling the passage of fluid through a pipe 68 leading to a number of whistles 69. As shown in the drawing, the two levers 59 and 36 are connected by a wire or rod 70, the points of connection being arranged to harmonize with the necessary movements of the two levers during the operation of the mechanism.

From the foregoing description, it is believed that the operation of my improved system, as thus far described, will be readily understood. If we assume that the pipe 68 leads from a steam generator or from a

source of compressed air, and also that the cut-off valve 67 is closed, and if we also assume that a fire occurs, and one of the call-boxes is operated, the description of the working of the mechanism will be as follows: Every time a space 13 of the disk 12 registers with the position of the metal contact 14, the call-box circuit will be broken and the magnet 5 deenergized. This results in the dropping of the lever 16 (see Fig. 1), whereby its electrode 18 is brought into contact with the adjacent electrode 20, thus closing the generator circuit through the solenoid 33, and shifting the lever 36 to the dotted line position in 32. In this event the path of the current may be traced as follows: from the pole 27 of the generator through the conductor 26, the part 25, the lever 16, the electrodes 18 and 20, the conductor 54, the binding post 53, the conductor 52 to the terminal 51 of the solenoid 33, through the coils of the said solenoid to the terminal 50 of the latter, and thence through the conductor 49 to the contact 48, and thence through the bar 36, the conductor 33, the binding post 31 and the conductor 30 to the opposite pole 29 of the generator. When the lever 36 is thrown to the dotted line position in Fig. 2 by the energizing of the solenoid 33, the lever 59 is also thrown to the dotted line position of the same figure, and the arms 65 actuated, as also indicated by dotted lines, to open the valve 67 and allow the operating fluid to pass to the whistles 69 and operate the same. Again as soon as the contact 14 (see Fig. 6) reaches a tooth or segment 4 of the disk 12 during its rotation in any call-box, the call-box circuit will be closed and the magnet 5 energized, with the result that the lever 16 will be brought to the position shown in Fig. 1, whereby the two electrodes 18 and 19 are brought into contact, thus closing the generator circuit through the solenoid 34, whereby the core 56 of the said solenoid will be drawn thereinto, shifting the lever 59 to the full line position in Fig. 2, and also the lever 36 to a corresponding position, and operating the parts 63 and 65 to close the valve 67. In this event the path of the current may be traced, as follows: from the pole 27 of the generator to the conductor 26, the lever 16, the electrodes 18 and 19, the conductor 47, the binding post 46, the conductor 45 to the terminal 44 of the solenoid 34, thence through the coils of the said solenoid to the terminal 43, thence through the conductor 42 to the contact 41, thence through the lever 36, the conductor 33, the binding post 31 and the conductor 30 to the opposite pole of the generator. It will thus be observed that every time there is a make and break in the circuit of the magnet 5, otherwise termed the call-box circuit, the solenoids 33 and 34 will be alternately

energized and the cut-off valve controlling the passage of fluid to the whistles, opened and closed. It will, therefore, be understood that by properly constructing the disk 12, any desired number of whistle signals may be given, the length of the period during which each whistle is sounded, depending upon the length of the spaces or recesses formed in the outer edge of a disk 12, hence 10 it is evident that by varying the construction of these disks for different call-boxes, the whistling signals resulting from the operation of any call-box, will indicate to a person understanding the system, the number of the said box.

Each solenoid is provided with a cushion A, located at the inner extremity thereof, and adapted to engage the movable core 56 or 89 as the case may be. This cushion 20 forms a stop to prevent the movement of the core farther than is necessary, in order to perform the required function, namely, the operation of the valve or of any other device with which my improved electromagnetic motor may be connected. This is important, since it is desirable that the work should be quickly performed. The cushion A is preferably composed of rubber, and should be so located as to stop the inward movement of the core after the latter has passed the point where it can be advantageously acted upon by the magnetic influence, since beyond this point the core simply travels by virtue of its momentum, and there is a 35 tendency to move it in the opposite direction. In order to prevent any undue resistance to the inward travel of the core by the formation of an air cushion, the rubber cushion A, as well as the cap or closure, at 40 the end of the case is provided with an air passage or duct B, whereby the air is allowed to escape freely.

It may be stated that my improved solenoid construction, may be employed to do 45 various kinds of work. In this application the operation of a valve for opening and closing a conduit, through which motive-fluid is passed to a motive-fluid-actuated-alarm device, is illustrated and described. 50 This disclosure is but one of the uses of my improved motor, as will be readily understood, but the invention is not limited thereto, as indicated by the scope of the appended claims.

55 The reason for using carbon contacts, as designated by the numerals 18, 19, 20, 73 and 74, is that the strength of the current required, in order to develop the necessary magnetism in the solenoids to perform the required work, is such that metal contacts would be fused, thus making it impracticable to employ anything but carbon or some other similar substance capable of resisting a high degree of heat, or which is practically 60 nonfusible in work of this kind.

Attention is called to the fact that independently of the rod 70, the bar 36 will be actuated, whereby it is caused to move from the full line position in Fig. 2 to the dotted line position in the same figure, when the 70 solenoid 33 is energized. In order that this result may occur, it is essential that the cap C of the solenoid shells should be formed of nonmagnetic material, so as to present the absorption of magnetism by these shells, 75 since to the extent of this absorption the magnetic influence available to act on the bar 36 would be reduced. It also follows from this statement that the same result will follow when the solenoid 34 is energized, 80 that is to say, if we assume that the bar 36 is in the dotted line position, it will be drawn by the magnetic influence to the full line position when the last named solenoid is 85 energized.

Having thus described my invention, what I claim is:

1. The combination of a motive-fluid-actuated signal, a valve for controlling the passage of fluid thereto, a pair of solenoids 90 connected in operative relation with the valve to open and close the same, an electromagnetic relay for alternately closing the circuit through the two solenoids, a solenoid circuit element actuated by each solenoid 95 when energized, to break the circuit of the energized solenoid, thus leaving both solenoids normally deenergized, substantially as described.

2. In an electric alarm, the combination 100 with a whistle, of a pipe communicating therewith, a source of motive fluid with which the pipe is also connected, a valve for controlling the flow of fluid from the said pipe to the whistle, a pair of solenoids provided with movable core members connected 105 in operative relation with the valve, a circuit in which the solenoids are located, a call box circuit, an electro-magnet located in the last-named circuit, an armature for the said 110 magnet, the armature being arranged in the solenoid circuit and adapted to alternately close the circuit through the magnets, and a solenoid circuit element actuated by each solenoid when energized to break the circuit 115 of the energized solenoid, for the purpose set forth.

3. In an electric alarm, the combination 120 with a motive fluid-actuated signal, of a pipe communicating therewith, a valve for controlling the passage of fluid through the said pipe to the signal, a pair of solenoids provided with movable core members, connected in operative relation with the valve, a 125 circuit in which the solenoids are located, a call box circuit, a magnet located in the last-named circuit, and a circuit make-and-break device located in the solenoid circuit, the said device being movably mounted and arranged to be operated by the magnet located in the 130

call box circuit to alternately close the circuit through the two solenoids, a solenoid circuit element actuated by each solenoid when energized to break the circuit of the energized solenoid, for the purpose set forth.

4. The combination with a signal adapted to be actuated by a motive fluid, a pipe carrying the said motive fluid and communicating with the signal, a valve for controlling the passage of fluid through the said pipe, a pair of solenoids connected in operative relation with the valve, a call-box circuit, a magnet located therein, and a movable member located in the solenoid circuit and adapted to be actuated by the magnet to alternately close the circuit through the two solenoids, and a solenoid circuit element, actuated by each solenoid when energized to

break the circuit of the energized solenoid, for the purpose set forth.

5. The combination of a motive fluid-actuated signal, a pair of solenoids for controlling the passage of motive fluid thereto, an electro-magnetic relay for alternately closing the circuit through the two solenoids, and means actuated by each solenoid when energized to break the circuit of the energized solenoid, thus leaving both solenoids normally deenergized, substantially as described.

In testimony whereof I affix my signature in presence of two witnesses.

PEABODY A. BROWN.
